(57) **CLAIM**

I claim the ornamental design for a urinal, as shown and described.

DESCRIPTION

FIG. 1 is a rear view of my urinal design with the lid attached in an assembled state.

FIG. 2 is a bottom perspective view of my urinal design with the lid attached in an assembled state.

FIG. 3 is a rear view of my urinal design with the lid detached.

FIG. 4 is a top view of my urinal design.

FIG. 5 is a left side view of my urinal design.

FIG. 6 is a rear view of my urinal design.

FIG. 7 is a right side view of my urinal design.

FIG. 8 is a rear view of my urinal design.

FIG. 9 is a top front perspective view of my urinal design.

FIG. 10 is a top rear perspective view of my urinal design.

FIG. 11 is a bottom view of my urinal design.

FIG. 12 is an alternative perspective view of my urinal design.

FIG. 13 is a top view of the lid of my urinal design.

FIG. 14 is a side view of the lid of my urinal design.

FIG. 15 is a bottom view of the lid of my urinal design.

FIG. 16 is a bottom perspective view of the lid of my urinal design; and,

FIG. 17 is an alternative bottom perspective view of the lid of my urinal design.

Broken lines in the figures indicate boundaries that form no part of the claimed design.
